UNITED STATES PATENT OFFICE.

GEORGE W. KING, OF BURRTON, KANSAS.

AUTOMATIC GATE.

Application filed December 19, 1924. Serial No. 756,915.

To all whom it may concern:

Be it known that I, GEORGE W. KING, a citizen of the United States, residing at Burrton, in the county of Harvey and State 5 of Kansas, have invented certain new and useful Improvements in an Automatic Gate, of which the following is a specification.

This invention relates to improvements in mechanically operated gates and has for its 10 principal object to provide one which is disposed across the roadway, the same being adapted to be opened automatically in either direction by the approach of a vehicle, thus obviating the necessity of the driver of the 15 vehicle having to leave the same and open the gate in order that the vehicle may pass through.

Another important object of the invention is to provide an automatic gate of the above 20 mentioned character, wherein means is provided for holding the gate in an open position so that a vehicle may pass therethrough, said means being adapted to be released when the vehicle has passed through the 25 gate opening, additional means being provided for returning the gate to its normal closed position.

A still further object of the invention is to 30 provide an automatic gate of the above mentioned character, which will at all times be positive and efficient in its operation, suitable trip mechanism for actuating the gate from either side being disposed within the road bed in the path of the wheels of a 35 vehicle.

A still further object is to provide an automatic gate of the above mentioned character, which is simple in construction, inexpensive, strong and durable and furthermore 40 adapted for the purposes for which it is designed.

Other objects and advantages of this invention will become apparent during the course of the following description.

45 In the accompanying drawing forming a part of this specification and in which like numerals designate like parts throughout the same:

Figure 1 is a top plan view of the automatic gate embodying my invention.

50 Figure 2 is a side elevation of the gate.

Figure 3 is a sectional view taken approximately on line 3-3 of Figure 2.

Figure 4 is a fragmentary detail showing 55 the segmental plate in side elevation supported on the lower end of the gate.

Figure 5 is a top plan view of one of the segmental plates.

Figure 6 is a fragmentary detail of the trip for actuating the rod and chain associated therewith, and illustrating the means for actuating the latch, and

Figure 7 is a fragmentary detail of the latch.

In the drawings, wherein for the purpose 65 of illustration is shown the preferred embodiment of my invention, the numerals 1 and 2 designate a pair of spaced posts which have their lower ends embedded in a roadway adjacent the side thereof. Disposed between the spaced posts is the gate 70 designated generally by the numeral 3 and the same may be of any conventional construction. The gate is hingedly supported at one end on the post 1 as illustrated at 4 75 and associated with the opposite end of the gate is a pair of slidable bolts 5 and 6 respectively, the same being adapted for engagement with suitable keepers 7 and 8 respectively, the latter being carried by the 80 post 2 as is more clearly illustrated in Figure 2 of the drawings.

The gate 3 is adapted to swing in a horizontal plane in either direction and for the purpose of normally holding the gate in 85 closed position between the posts 1 and 2, a coil spring 9 is associated with the hinged end of the gate and the post 1. An extension 10 is formed on the lower end of the hinged end of the gate and is preferably 90 in the form of a shaft. The extension is disposed downwardly through the top of a suitable housing 11 which is set in the roadway A adjacent the post 1, the shape of the housing or casing 11 being more clearly illustrated in Figures 1 and 3 of the drawings. The top of the casing is furthermore adapted to extend substantially flush with the surface of the roadway as clearly illustrated in Figure. 2. 100

A pair of segmental plates 12 and 13 respectively are adapted to be secured in spaced relation on the lower end of the shaft 10 and disposed within the housing or casing 11. Each of the segmental plates 105 is provided with a collar 14, and a set screw 15 is provided for securing each of the collars of the segmental plates in a rigid position on the lower end of the shaft 10. Notches 16 and 17 are provided in the peripheral edges of the segmental plates 12 and 13 respectively and the purpose thereof 110

will hereinafter be more fully described.

A pair of levers 18 and 19 are associated with the segmental plates 12 and 13 respectively. The levers are rotatably supported 5 on the collars of the respective segmental plates adjacent the inner ends of the levers, the outer ends of the levers extending beyond the segmental plates in the manner clearly illustrated in Figures 3 and 4.

10 The inner ends of the levers are connected to suitable chains 20 and 21 respectively, the same extending over suitable pulleys and extending upwardly through the casing and being fastened to a chain 22 which extends across the gate 3 and is secured to the bolts 5 and 6 by means of the chains 23 and 24. The purpose of this construction will hereinafter be more fully described.

15 Slidably mounted in suitable guides 25 and 26 carried by the outer ends of the levers 18 and 19 respectively are the plungers 27 and 28. The inner ends of the plungers are adapted for cooperation with the notches 16 and 17 respectively and are normally held 20 out of engagement therewith by means of the coil springs 29. Arms 30 and 31 are pivotally supported on the outer ends of the levers 18 and 19 respectively. The inner ends of the arms are secured to the outer 25 ends of the respective plungers by suitable link connections such as is more clearly illustrated in Figure 3. The operation of the plungers will also hereinafter be more fully described.

30 A chain 32 is secured at one end to the outer end of the arm 30 and a similar chain 33 is secured to the outer end of the other arm 31. The chain 32 extends through an opening 34 provided in the inner side of the casing and extends over a suitable pulley 35 supported by the post 1 adjacent the surface 35 of the roadway. The chain 33 extends through a suitable opening 36 formed in the inner side of the housing or casing 11 opposite the opening 34. The chain 33 is disposed over a suitable pulley 37 which is also supported by the post 1 and is spaced from the pulley 35 so that the chains will extend in the opposite direction.

35 A rod 38 is secured to the end of the chain 32 and extends longitudinally adjacent the surface of the roadway A on one side of the fence, a similar rod 39 being secured to the end of the other chain 33 and extending along the side of the roadway on the opposite side of the gate. The rods are of a suitable length and are pivotally connected at their outer ends to the lower ends of a pair of trip levers 40 and 41 respectively. Each of the trip levers is pivoted adjacent its lower end on a suitable block 42 and a lateral extension formed on the upper end of each of the trip levers is disposed inwardly so as to be within the path of the wheels of 40 a vehicle when the same approaches the gate.

Vertical standards 43 and 44 are disposed on opposite sides of the gate at a point intermediate the blocks and the post 1. A latch 45 is pivotally supported on the upper end of each of the standards, the same being 70 adapted for cooperation with the top of the gate 3 when the latter is swung in an open position in either direction, in a manner which will be presently apparent. Each of the latches is operated by means of an elongated rod 46 which is pivotally secured to the inner end of each latch, the rod 46 extending downwardly and being connected at its lower end to one end of the bell crank lever 47 which is pivotally supported as at 48 on the lower end of each of the standards. The opposite end of each of the bell crank levers is slidable on the rods 38 and 39 respectively. The rods 38 and 39 are slidable through eye bolts 51 extending from post 43. Springs 85 51 and 52 are disposed on the rods 38, 39 and impinge against pins 49 and 50 passing through the rod 38, 39 and against the eye bolt, and normally hold the rods 38 and 39 and associated parts in their normal positions after they have once been actuated. The bell crank levers 47 are provided with slots for receiving the rods 38, 39, and the pins 50 will engage said ends of the levers to actuate them for releasing the latch 45 which will otherwise gravitate to the engaging position shown in Figure 7.

90 The operation of my improved automatic gate may be briefly stated as follows: Normally the gate is held in a closed position by means of the coil spring 9 and the bolts 5 and 6 which cooperate with the keepers 7 and 8. When a vehicle approaches the gate on one side thereof, the wheels of the vehicle will pass over the trip 40 which is located 100 at a point remote from the gate causing the rod and chain 38 and 32 respectively to be pulled in the direction of the arrows whereby the lever 18 will be caused to rotate on the collar of the segmental plate 12 and cause the bolts 5 and 6 to be disengaged from the keepers 7 and 8. Simultaneously, the plunger 27 will be brought into engagement with the notch 16 and the segmental plate 12 will be caused to rotate, simultaneously 105 causing the swinging movement of the gate 3 in an open position away from the vehicle until the latch on the upper end of the standard 44 engages the top of the gate, thereby holding the gate open so as to permit the vehicle to pass through the gate opening.

110 After the vehicle has passed through the gate opening, the wheels will come in contact with the trip 41 disposed on the opposite side of the gate and the movement of the trip 41 in one direction will cause the operation of the rod 39 to release the latch on the standard 44 from engagement with the gate 3 and the spring 9 which has been 115 120 125 130

placed under tension during the opening of the gate will then return the same to its normal closed position. Manifestly, the gate

5 will be opened in the same manner but in opposite direction when a vehicle approaches the gate from the opposite side, the trip 41 being initially actuated to open the gate through the medium of the lever

19 and the segmental plate 13.

10 The provision of an automatic gate of the above mentioned character, will save considerable time and labor and furthermore will obviate the necessity of the driver leaving his seat to open the gate in order that the vehicle may pass through the gate opening. Furthermore, a gate structure of

15 the character above described will at all times be positive and efficient in its operation.

20 While I have shown the preferred embodiment of my invention, it is to be understood that various changes in the size, shape and arrangement of parts may be resorted to without departing from the spirit of

25 the invention and the scope of the appended claims.

Having thus described the invention, what I claim is:—

1. In combination, a pair of posts, a gate hinged to one post, latch means associated with the other post and the free end of the gate, a shaft on the hinged end of the gate, a segmental plate keyed to the shaft, a lever rotatably mounted on the shaft, a chain leading from the lever to the latch means, a plunger slideable on the lever, the arcuate plate having a notch engageable by the plunger, a spring normally holding the plunger out of engagement with the notch,

40 an arm pivoted to the lever, a link connecting one end of the arm with the plunger,

a chain attached to the other end of the arm, and means for pulling the last chain, thereby swinging the arm and engaging the plunger in the notch, at the same time 45 swinging the lever to pull the first chain so as to release the latch means and as the last chain is further pulled, the lever locked to the segmental plate by the plunger will rotate the shaft and swing the gate, means for releasably latching the gate in open position, and spring means for closing the gate.

2. In combination, a pair of posts, a gate hinged to one post, spring means for normally holding the gate in a closed position between the posts, latch means associated with the other post and the free end of the gate, a shaft on the hinged end of the gate, a segmental plate keyed to the shaft and provided with a notch, a lever rotatably mounted on the shaft, a chain leading from one end of the lever to the latch means, a plunger slideable on the lever and engageable with the notch in the arcuate plate, 55 a spring normally holding the plunger out of engagement with the notch, an arm pivoted to the lever, a link connecting one end of the arm with the plunger, a chain attached to the other end of the arm, a vehicle 60 operated actuating member associated with said chain for pulling said chain when a vehicle engages the same from one side to thereby release the latch and open the gate, means for releasably engaging the gate to hold it in an open position, and vehicle 65 actuated means on the other side of the gate being associated with said last mentioned means for releasing the said engaging means.

In testimony whereof I affix my signature.

GEORGE W. KING.
